UNITED STATES PATENT OFFICE.

HENRY MAYO HAINES, OF WALTHAM, MASSACHUSETTS.

STEM WINDING AND SETTING MECHANISM FOR WATCHES.

SPECIFICATION forming part of Letters Patent No. 308,409, dated November 25, 1884.

Application filed April 17, 1884. (No model.)

To all whom it may concern:

Be it known that I, HENRY M. HAINES, of Waltham, county of Middlesex, State of Massachusetts, have invented an Improvement in 5 Watches, of which the following description, in connection with the accompanying drawings, is a specification, like letters on the drawings representing like parts.

My invention, relating to stem winding and 10 setting watches, is intended as an improvement in watches of that class in which the stem actuates a gear or toothed wheel, which in turn actuates other toothed wheels supported on a movable plate or swinging yoke operated by 15 a shifting-lever, by means of which one or the other of the latter wheels may be placed in position to actuate the mainspring winding-shaft or the hands, according as it is desired to wind or set the watch.

20 The invention consists, mainly, in a novel construction of the devices by which the hands are engaged, and of the shifting-lever, and in the combination, with the said lever and mechanism controlled by it, of a locking device for 25 holding the said lever in its different positions, the object of such novel construction being to afford increased convenience and certainty in operation, as well as greater convenience in assembling the parts in the watch.

30 Figure 1 is a plan view of a watch containing winding and setting mechanism embodying my invention, the shifting-lever being in contact with the yoke and locked, with the winding mechanism out of engagement and 35 the setting mechanism in engagement. Fig. 2 is a similar view showing the winding mechanism in engagement and the setting mechanism out of engagement.

40 In the annexed drawings, *a* represents the ordinary bevel-pinion, with which the stem (not shown) of the watch is connected, and which engages the bevel-gear *a'*, loose on the hub *b*, carrying the yoke *B*, arranged above or outside of the bevel-gear, (also not shown,) 45 the said yoke having the winding intermediate *c*, meshing with the gear *a'*, and when the yoke is in its normal position, as shown in Fig. 2, also meshing with the mainspring-gear *C* to complete the train of mechanism 50 from the stem to the mainspring-shaft, whereby the winding of the mainspring is effected. The usual pawl, *c'*, actuated by a spring, *c''*,

engages the mainspring gear *c* to prevent backward movement thereof, and the yoke *B* has an arm, *2*, which extends beyond the winding intermediate to engage a stud, *3*, and limit the inward movement of the yoke when the winding mechanism is thrown into engagement, as shown in Fig. 2. Motion is transmitted from the gear *a'*, loose on the hub *b*, to the minute-hand shaft by means of two intermediate or toothed wheels, *d* *d'*, arranged one above the other, and connected to rotate together on a common arbor or journal, which is supported in an extension of the yoke *B* on the 65 opposite side to that carrying the winding intermediate *c*, the upper or outer intermediate, *d*, meshing with the gear *a'*, and the lower or inner intermediate, *d'*, having pointed or V-shaped teeth to engage similar-shaped 70 teeth on the disk *e*, fixed on the minute-hand or cannon-pinion *n*. The V-shaped teeth facilitate the engagement of the intermediate *d'* with the disk *e* when it is desired to throw the setting mechanism into engagement, as will be 75 presently indicated, and produce no jumping or turning of the hands when the setting mechanism is thrown into or out of engagement therewith. The yoke *B* is loose on its hub, and normally the winding mechanism is retained 80 in engagement and the setting mechanism kept out of engagement (see Fig. 2) by means of a spring, *f*, secured to the frame, and having its free end engaging a pin, *f'*, fastened to the yoke, as indicated in the drawings. 85

To reverse the position of the parts, or throw the winding mechanism out of engagement and the setting mechanism into engagement, I provide a shifting-lever, *i*, pivoted at *i'*, and constructed substantially as shown—that is to 90 say, substantially of Z form—the arm *i''* thereof passing through the side or rim of the frame, to enable it to be caught by the operator and drawn outward to bring the other arm, *i''*, into engagement with a projection, *4*, on the yoke *B*, and cause said yoke to swing or partially rotate on its hub, whereby the winding intermediate will be withdrawn from engagement with the mainspring-gear *C* to disconnect the winding mechanism, and the inner intermediate *d'*, having the V-shaped teeth and journaled to the opposite end of the yoke, will be 95 brought into engagement with the toothed disk *e* on the minute-hand arbor, when the set- 100

ting mechanism will be in condition to be operated, all as fully shown in Fig. 1. The arm i^3 of the shifting-lever is rigid, and, in acting on the projection 4 of the yoke or plate B, turns 5 the said yoke positively for a definite distance sufficient to engage the teeth of the disk e and intermediate d' , without, however, pressing the teeth together, so as to bring a lateral strain on the arbor that carries the hands, and 10 the shifting-lever is easily operated, as it has but slight force to overcome. A spring, k, formed in the present instance in one piece with the spring f, has a V-shaped projection, k', on its end, to engage the pin, k^2 , on the under side of the lever i and hold said lever in engagement with the projection on the yoke B, as shown in Fig. 1, whereby the parts are locked in such position until it is desired to 15 again put the winding mechanism into position to operate, which is accomplished by pressing on the arm i^3 to disengage the lever from the projection on the yoke, the pin k^2 sliding over the projection k' on the spring k, when the spring f will cause the yoke to move 20 on its hub, as stated, to engage the winding intermediate with the mainspring-gear. When the parts are in the normal position shown in Fig. 2, the minute-hand shaft, with its toothed disk, may be removed from the frame without 25 disturbing the described winding or setting mechanism, the two intermediates d d' being sufficiently withdrawn from the disk on the minute-hand arbor to readily permit such manipulation of the parts. The pinion n on 30 the minute-hand arbor engages with train for imparting movement to the hour-hand, which is not herein shown. The setting-disk e is securely fastened to the minute-hand arbor or cannon-pinion n, and the setting intermediates 35 d d' are also securely fastened or staked together, so that they rotate as a single piece. By having the two intermediates d d' the former may have fine-pointed teeth, which are 40 easily brought into engagement and operate 45 more perfectly than a single intermediate adapted to engage both the actuating-gear a' and a pinion or toothed wheel on the minute-hand arbor.

Great difficulty has heretofore been experienced in setting mechanism applied to 50 watches on account of the jumping or movement of the minute-hand upon connecting the setting mechanism therewith to set the hands. To effectively overcome this difficulty I provide the locking-spring having the V-shaped projection to securely lock the lever when 55 pulled out to move the swinging yoke. The

yoke-actuating spring causes the projection 4 on the yoke to be closely pressed or held against the inner arm of the shifting-lever as 60 locked by the locking-spring, whereby I am enabled to attain a full and delicate engagement of the setting intermediate with the setting-disk of the minute-hand arbor, wherein the teeth of the pinion are prevented from bottoming in the teeth of the setting-disk. If 65 the pinion and disk were brought into close contact, so that the teeth of the one bottomed in those of the other, roughness of action between the two would take place, and would 70 show itself in the jumping of the minute-hand when the setting mechanism was brought into engagement with the minute-hand arbor. Further, it is important that the lever should be securely locked after having been brought 75 into engagement with the projection 4 of the yoke; otherwise by the action of the yoke-actuating spring the lever would be caused to slip from the projection 4, and thus throw the parts out of engagement. Without the locking-spring the lever would have to be of such 80 increased length as to force the setting intermediate and disks rigidly together in order to make the lever hold on the projection 4, and the consequence of this would be a jumping 85 of the hands when the setting mechanism was thrown into as well as out of engagement with the minute-hand arbor.

I claim—

1. The combination, substantially as described, of the swinging yoke provided with a projection, 4, the spring f, engaging said yoke, the actuating-lever, substantially of Z form, with one arm adapted to engage the projection on the yoke, and the other arm passing the rim of the frame or casing, and the spring k, having the projection k' , adapted to engage the pin k^2 on the under side of the lever, for the purpose set forth. 90

2. The minute-hand arbor provided with a toothed setting-disk, and the actuating-gear and swinging yoke provided with a setting intermediate, combined with the shifting or actuating lever adapted to engage the said yoke and move it a definite distance, and the spring 95 with a V-shaped projection co-operating with the said lever, substantially as described. 100

In testimony whereof I have signed my name to this specification in the presence of two subscribing witnesses.
